(57) **CLAIM**

The ornamental design for a LED lamp as shown and described.

DESCRIPTION

FIG. 1 is a perspective view of a LED lamp, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is perspective view of the LED lamp in an alternate configuration of use;

FIG. 10 is a perspective view of the LED lamp in a second alternate configuration of use;

FIG. 11 is a perspective view of the LED lamp in a third alternative configuration of use;

FIG. 12 is a perspective view of the LED lamp in a fourth alternate configuration of use; and,

FIG. 13 is a detailed view of the circled portion of FIG. 1. The alternating-length broken lines in FIGS. 1 and 13 depict the boundaries of the enlarged fragment and form no part of the claimed design.
